COMPOSITE SHINGLE

Hubert Porter Taylor, Union City, Tenn., assignor of one-half to Robert H. Taylor, Martin, Tenn.

Application July 13, 1932. Serial No. 622,357

2 Claims. (Cl. 108—8)

The invention relates to a new and improved shingle embodying a concrete slab upon a weather-proof backing sheet, and the principal object of said invention is to provide a perfect bond between said slab and sheet which will prevent separation of the sheet from the slab even if the shingles be laid upon spaced roofing lath instead of upon tight sheathing and will retain all parts of the slab upon the sheet if said slab should become cracked or even more or less shattered, and to provide for cementing of each shingle to underlying shingles under the influence of sun heat after the roofing is laid. Thus, the component parts of the individual shingles are tenaciously joined together even if some of the slabs be cracked or more severely injured, and the various shingles become tightly cemented to each other, forming virtually a single-sheet roof which will be fireproof, weatherproof even against driving rains, will insulate against heat, sound and electricity, and will be practically everlasting.

With the foregoing in view, the invention resides in the novel subject matter hereinafter described and claimed, description being accomplished by reference to the accompanying drawing.

Fig. 1 is a top plan view of a composite shingle constructed in accordance with the invention.

Figs. 2 and 3 are longitudinal and transverse sectional views on lines 2—2 and 3—3 respectively of Fig. 1.

Fig. 4 is an enlarged fragmentary transverse sectional view similar to a portion of Fig. 3.

In the drawing above briefly described, the numeral 5 denotes a backing sheet preferably formed from two or more layers of roofing felt, building felt, deadening felt, or the like, suitably weatherproofed (for instance by saturation with a bituminous compound) and tightly cemented and pressed together. The entire lower side of this sheet 5 is provided with a layer 6 of bituminous or other mastic cement which possesses a melting point adapting it to soften sufficiently under the influence of sun heat, to allow any shingle to adhere to the underlying shingles. A myriad of mineral fragments 7 which may be the size of peas, are partially embedded in the upper side of the backing sheet 5 and are secured thereto, said fragments projecting about half into and half above said sheet.

A concrete slab 8 is poured, rattled, rammed, pressed or otherwise formed on the fragments 7 and the sheet 5 so that the projecting portions of said fragments become embedded in the concrete, forming a tenacious and permanent bond

between the sheet 5 and the slab 8. This slab is preferably somewhat larger than the sheet 5 and is provided with a continuous marginal rib 9 which surrounds the edge of said sheet, providing a further bond between sheet and slab, and protecting the edge of the former. The rib 9 does not extend downwardly any further than the lower side of the mastic cement layer 6 and need not extend entirely to the lower side of said layer.

The entire shingle is preferably tapered as shown in Fig. 2, and while said shingle may be constructed in various dimensions, it may well be eighteen inches long, eight inches wide, five-eighths of an inch thick at its lower end, and three-eighths of an inch thick at its upper end. The backing sheet 5 may obviously be formed of any desired weatherproof or weatherproofed material to prevent leakage even should the slab 8 become cracked or even shattered. The mineral fragments 7 form such a tenacious bond between this backing sheet 5 and the concrete slab 8, that even if the latter should become badly broken, all parts of it will still remain in proper position upon said backing sheet. Moreover, this tenacious bond between slab and backing sheet, prevents the latter from separating from the slab even if the shingles be laid upon widely spaced roofing lath instead of upon tight sheathing. For greater strength and to minimize danger of breakage, particularly when the shingles are used on roofing lath, the slab 8 may be provided with any desired reinforcing means, a plurality of wires 10, preferably of steel being shown for this purpose.

A roof constructed from the improved shingles, becomes virtually a one-piece sheet, for the component parts of each shingle are tenaciously bonded together, and the shingles become tightly cemented to each other by the cement 6, said cement becoming sufficiently viscous to function in this manner, due to the heat of the sun upon the roof. A roof is thus provided which will be weatherproof even against rains blown by hard winds, will be fire-proof, will insulate against heat, sound and electricity, and will be practically everlasting.

Each individual shingle may be of any proportions and of any desired color or shade or any combination of them attained either by ad-mixture to the concrete or by application to the surface, or of a colored surfacing added during or after manufacture. The part of the shingle that is exposed to the weather may be of any desired texture, or be given any desired surface treat-

ment, be smooth, sand or brush finished and carry a complete design or a portion of one, either depressed into the surface, flush with it or in relief.

5 I claim:—

1. A composite shingle comprising a concrete slab, a water-proof sheet secured against the lower side of said slab, and a layer of mastic cement upon the lower side of said sheet, said mastic cement having a melting point adapting it to soften sufficiently under sun heat to adhere to the concrete slabs of underlying shingles, said sheet being of slightly less area than said slab, the latter being provided with a marginal rib surrounding the edge of said sheet, said rib extending downwardly no further than the lower side of said mastic cement layer.
- 10 2. A composite shingle comprising a water-proof sheet, a myriad of mineral fragments em-

bedded partially in the upper side of said sheet and secured thereto, portions of said fragments projecting upwardly from said sheet, a concrete slab upon said sheet, the projecting portions of said mineral fragments being embedded in the concrete of said slab, and a layer of mastic cement on the lower side of said sheet having a melting point adapting it to soften sufficiently under sun heat to adhere to the concrete slabs of underlying shingles, whereby the component parts of each shingle of a roof will be tenaciously bonded together and all of the shingles will become cemented together, said sheet being of slightly less area than said slab, the latter being provided with a marginal rib surrounding the edge of said sheet, said rib extending downwardly no further than the lower side of said mastic cement layer.

HUBERT PORTER TAYLOR.
